FREDERICK W. EAGER, OF QUINCY, MASSACHUSETTS, ASSIGNOR TO HARRY H. BECK,
WITH, OF BROOKLINE, MASSACHUSETTS

METHOD OF SOFTENING SHOE STIFFENERS

Application filed June 1, 1927. Serial No. 195,808.

It is now common practice to incorporate stiffening members in shoes, such stiffening members containing thermoplastic material which may be softened when subjected to 5 moderate heat so that the stiffeners may be made sufficiently limp to permit them to be shaped to the lasts during the manufacture of the shoes. In order to soften the stiffeners in this manner, it has been customary to insert the shoe portion containing the stiffener in a heater in which the shoe upper material at least is subjected to moist heat. This method has been satisfactory in most cases for the heavier grades of leather, but has been 10 unsatisfactory when the shoe uppers have been composed of delicate or highly colored or embossed leather, the more highly colored leather tending to be more or less bleached, the delicate or light colored to be stained, 15 and the embossing of embossed leather made less pronounced by this treatment. Where the upper has cutouts or perforations therethrough this method has not been entirely satisfactory, particularly where the usual 20 cabrettas are used as lining material as this material is shrunk and turned dark thereby. 25

Sometimes colored surfaces for leather are produced by applying successive coatings of different colors, the underlying colors implying 30 a modification to the surface colors of the completed products. When such leather is subjected to the moist hot vapor treatment as heretofore practiced, underlying colors are brought to the surface more decidedly 35 so that a staining effect results.

I have concluded as the result of much experience that the moist heat of itself does not cause this damage to the leather, but that it is due to the fact that when shoes are placed 40 therein they are relatively cold, this causing an initial condensation of moisture which, as the shoe parts are raised in temperature to substantially that of the vapor, is re-evaporated. I believe that it is this free moisture 45 absorbed by the shoe material prior to the shoe reaching substantially the temperature of the moist vapor that does the damage.

According to the present invention, therefore, this condensation of moisture on the 50 upper material is prevented. A method

which I have found most effective for the purpose is to cover the shoe part which is to be inserted in the heater with a dry fabric on which the initial condensation is deposited, the fabric being of sufficient weight to prevent the moisture from striking through onto the shoe during the time necessary to raise the shoe and fabric to a temperature sufficiently high to cause re-evaporation of the condensate. When toe stiffeners are to be 55 softened the fabric may conveniently be formed into a bag having an open end which may be drawn over the toe of the shoe to be treated prior to its insertion into the toe heater. Fabric which has been found quite 60 suitable for the purpose is 7 ounce cotton duck. When made into a bag and drawn over the toe portion of the shoe it not only 65 protects the upper, but it also protects the sole or insole from the moisture. Heretofore, 70 shoe heaters have commonly been made with means for supplying dry heat to contact with the innersole, it having been found that the moist heat is likely to damage the innersole. By protecting the innersole from the initial 75 condensation, as by means of the fabric, the need for dry heat is entirely avoided, so that less complicated heating mechanism may be entirely satisfactory.

For a more complete understanding of this 80 invention, reference may be had to the accompanying drawings showing the invention as applied to the softening of toe stiffeners and in which

Figure 1 is a perspective of the fabric bag 85 for use in connection with the practice of this invention.

Figure 2 is a central longitudinal section through the same showing in dotted lines the position of a shoe with relation thereto in 90 condition for insertion in the heater.

Figure 3 is a vertical section, somewhat diagrammatic, through one form of heater showing the shoe toe encased in the bag in 95 position therein for the softening operation.

Referring to these drawings, at 1 is indicated a fabric bag having an open end 2, the bag being so shaped that it may be drawn over the toe portion of a shoe as shown in Figure 2, the shoe being indicated at dotted lines at 3. 100

The bag may be made in any suitable manner, but as shown it is composed of a pair of mating sections 4 and 5, the edges of which are brought together and stitched as at 6. The bag thus formed may be drawn over the toe of the shoe so as to embrace the same fairly closely and the shoe toe with the bag thereon is then thrust into the moist heat in the treating chamber 10 of the heater 11, as shown in Figure 3, the bag being of sufficient length to cover all of the shoe which might otherwise be reached by moisture from the heater. While any ordinary type of moist heat shoe heater may be used, as shown in this figure, the moist heat rises through a mass of fibrous material 12, in the base of the chamber 10, this material being held in position by means of a wire screen 13 placed thereabout. Moist vapor is supplied to the interior of the chamber 10 continuously by any suitable means so as to maintain the atmosphere therein at a temperature sufficiently high to soften the thermoplastic material in the toe stiffener. When the shoe toe with the bag thereon, which is at ordinary room temperature, is inserted into the chamber 10, the vapor impinging thereon is immediately condensed, the condensate being caught by the bag and prevented thereby from passing through and reaching the shoe parts within the bag. The bag and shoe are then brought up to substantially the temperature of the vapor within the chamber 10, whereupon the condensate is again vaporized, the moisture within the chamber 10 being somewhat less than at the saturation point, and the toe stiffener is softened while the moisture in the vapor prevents injury to the upper leather. When the stiffener has been softened to the desired degree the shoe and bag may be removed, the bag removed from the shoe, and the forming operations on the shoe toe completed. The initial heating of the shoe is thus produced by substantially dry heat, the bag delaying the contact of the moisture with the shoe until such time as the shoe has been raised to a temperature sufficiently high so that moisture from the vapor will not be condensed on the shoe. By this procedure all the toe portion, and more especially the parts exposed in the finished shoe, such as the outer face of the upper material is protected from the initial condensation and its color preserved.

In order that the fabric protective member comprising the bag 1 may properly perform its function it is quite essential that it be dry, or at least so nearly so that it does not permit any free moisture to come into contact with the shoe.

Having thus described the nature of this invention, it should be evident to those skilled in the art that various changes and modifications might be made from the specific method and means herein shown without de-

parting from its spirit or scope as defined by the appended claims.

I claim:

1. The method of conditioning for shaping shoe parts including thermoplastic stiffeners, which comprises covering such parts with a dry protecting fabric, and then subjecting said parts to the action of hot vapor for a time sufficient to soften the stiffeners sufficiently for the shaping operations. 70

2. The method of softening the toe portion of a shoe containing a thermoplastic stiffener, which comprises drawing a dry fabric bag over said portion, and then subjecting said portion while in the bag to moist hot vapor. 80

3. The method of softening the toe portion of a shoe containing a thermoplastic stiffener, which comprises heating such portion in moist vapor while the surfaces exposed in the finished shoe are protected from access by 85 condensation from said vapor.

4. The method of softening the toe portion of a shoe containing a thermoplastic stiffener, which comprises heating such portion in moist vapor while covered with an initially 90 dry fabric of substantial weight.

5. In the process of conditioning for shaping shoe parts including thermoplastic stiffeners by subjecting them to moist hot vapor, the method of preventing damage to such parts which comprises delaying contact of the moisture of said vapor therewith until said parts become heated to such a temperature that no condensation of vapor thereon occurs on such contact. 95

6. In the process of conditioning for shaping shoe parts including thermoplastic stiffeners by subjecting them to moist hot vapor, the method of preventing damage to such parts, which comprises heating said parts with relatively dry heat to such a temperature that moisture from said vapor will not be condensed thereon and then subjecting them to such vapor. 105

In testimony whereof I have affixed my signature.

FREDERICK W. EAGER.
